M. B. BEHRMAN

CHECK PROTECTOR

Filed Sept. 7, 1922

By his Attorney: *MARCUS B. BEHRMAN.*

Charles C. Gill.

UNITED STATES PATENT OFFICE.

MARCUS B. BEHRMAN, OF NEW YORK, N. Y.

CHECK PROTECTOR.

Application filed September 7, 1922. Serial No. 586,589.

To all whom it may concern:

Be it known that I, MARCUS B. BEHRMAN, a citizen of the United States, and a resident of New York city, in the county of New York and State of New York, have invented certain new and useful Improvements in Check Protectors, of which the following is a specification.

The invention relates to means for preventing the figures or writing on a bank check or like paper from being successfully altered by erasure or otherwise, and more especially to a small check protector adapted to be carried in a vest or other pocket and preferably on a fountain pen so as to be handy for use by a person employing a pocket check book.

In its preferred form the check protector of my invention comprises a toothed roller and a roller ink-pad therefor, said toothed roller having a series of annular rows of teeth and being adapted when rolled under pressure on the writings or figures on a bank check to puncture the paper of the check in such effective manner as to prevent alteration in such writings or figures, which denote the amount or face value of the paper, said toothed roller, also, when in use, rolling against the ink-pad and, becoming inked, making an ink impression on the check while puncturing the same, the ink impression being approximately in the form of dots corresponding with the teeth on the roller or the punctures made thereby and cooperating with the punctures in preventing the successful alteration of the check. The toothed puncturing roller and the roller ink-pad are mounted in suitable bearings carried by a frame which may be applied to or form a permanent part of the cap of a fountain pen, and said rollers when not in use are concealed by a cap applied over them and preferably representing an extension of the casing of the pen. The check protector of my invention may be made use of whether on or off from a fountain pen, and in every instance the protector is efficient, small and compact and may be carried on the person so as to be convenient of use at any time a check is drawn.

The invention will be fully understood from the detailed description hereinafter presented, reference being had to the accompanying drawings, in which:

Fig. 1 is a side elevation of a fountain pen equipped with a check protector embodying my invention;

Fig. 2 is a vertical section, on a larger scale and partly broken away, of the same taken on the dotted line 2—2 of Fig. 1;

Fig. 3 is a vertical section, taken at right angles to the section of Fig. 2, of my check protector detached from the fountain pen;

Fig. 4 is a transverse section through the same, taken on the dotted line 4—4 of Fig. 2;

Fig. 5 is a side elevation, partly broken away and partly in section, of a fountain pen whose cap has directly and permanently applied thereto the check protector of my invention;

Fig. 6 is an enlarged vertical section of a modified construction of check protector embodying my invention;

Fig. 7 is a detached perspective view of one member of the check protector shown in Fig. 6, and

Fig. 8 is a side elevation, partly in vertical section, of the check protector of Figs. 1 to 4 inclusive applied to a tube to be used as a handle in lieu of being applied to a fountain pen.

In the drawings 10 designates a fountain pen of usual type having a cap 11 to close over the pen-point when necessary.

The check protector of my invention, as illustrated in Figs. 1 to 4 inclusive, includes means for detachably applying the same upon the closed end of the cap 11, and said check-protector comprises a base frame 12 concaved on its lower side to closely fit the end of the cap 11 and having downwardly extending fingers 13 adapted to closely bind against the sides of said cap and thereby retain the check device upon said cap. The base 12 is of circular outline and formed with an annular shoulder 14 and an upwardly extending sleeve 15, which is screw-threaded on its exterior and recessed at opposite points of its upper edge to form bearings for the ends of the axle 16 of a soft roller ink-pad 17.

Upon the lower exterior portion of the sleeve 15 is a ring jamb-nut 18 whose exterior vertical edge is about on the same plane with the outer edge of the shoulder 14. Upon the upper portion of the sleeve 15 I apply the puncturing-roller carrying frame 19 comprising an annular base-portion 20 and a vertical downwardly projecting tubular portion or flange 21 which is internally and externally threaded and which is screwed downwardly upon the sleeve 15 of the base 12. The frame 19 is

formed at opposite sides of the base-member 20 with vertical standards 22 having vertically elongated bearing openings 23 in which I mount the ends of the shaft or axle 24 of the puncturing roller 25, the elongation of the openings 23 being, for one purpose, to permit the roller 25 to yieldingly engage the roller-pad 17 when the roller 25 is being pushed along over the surface of 5 a check or the like. The roller 25 is of steel and formed with a series of annular side by side rows of sharp-pointed teeth, as shown in Figs. 2 and 3, and said roller 25 is of suitable width to puncture, when rolled 10 over the same, the portions of a check or the like on which the amount or face value has been written or printed. The frame 19 carrying the roller 25 will be screwed downwardly upon the sleeve 15 until the lower edge of 15 the roller is in suitable relation to the ink roller 17, the final intention being that when the roller 25 is rolled against the surface of a check, said roller will also roll against the ink roller 17 and being inked 20 thereby, will transfer the ink to the punctures in the check made by the teeth of the roller, there thus being a double safeguard in the use of my invention, one being the puncturing of the check by means of the 25 roller and the second being the inking of the check at the punctures made by the roller. When the check-protector is not in use I apply a cap 26 over the same, said cap being of sheet metal and threaded within 30 its lower annular portion to be screwed upon the threaded flange 21 of the frame 19, as shown in Figs. 2 and 3, the cap 26 harmonizing in general appearance with the 35 end of a fountain pen and hence not being 40 objectionable in appearance.

In assembling the parts of the check protector the axle 16 for the pad-roller 17 is dropped into its bearing recesses in the sleeve 15, and thereupon the frame 19 carrying the toothed roller 25 is screwed downwardly upon the said sleeve. In applying the frame 19 to the sleeve 15 I maintain the axle 24 of the toothed roller 25 at the upper ends of the slots 23 in the standards 22, so 45 that while screwing the frame 19 downwardly upon the sleeve 15, the lower edge of the roller 25 may not scrape against the pad-roller 17. After the frame 19 has been sufficiently applied to the sleeve 15 and the 50 roller 25 is in parallelism with the pad-roller 17, I secure the frame 19 rigidly upon the sleeve 15 by means of the jamb-nut 18, said nut 18 when the frame has reached its 55 final position being rotated upwardly 60 against the lower edge of the flange 21 thereof for locking the frame 19 with its roller 25 in fixed relation to the sleeve 15 and roller 17. The elongated slots 23 in the standards 22 permit me to keep the roller 25 in an elevated position while applying

the frame 19 to the sleeve 15, and the threaded flange 21 enables me to secure a light engagement of the roller 25 and pad-roller 17, as shown in Fig. 3, which will be maintained during the non-use of the protector. 70 When the protector is in use the pressure against the roller 25 will cause said roller to move more firmly against the pad-roller 17 and receive its supply of ink therefrom, the elongated slots 23 permitting the roller 25 to move against the roller 17 when said roller 25 is under pressure, as in use. 75

After the several parts of the interior mechanism have been assembled, as shown 80 in Figs. 2 and 3, the cap 26 is screwed downwardly upon the flange 21 until it engages the jamb-nut 18.

The modification shown in Fig. 5 resides merely in forming the base, numbered 12 in Fig. 3, directly on the end of the cap 30 of 85 a fountain pen 31 and in the consequent omission of the clamping fingers 13. In Fig. 5 I number the base of the protector 27, and this base 27 has a shoulder 28 corresponding with the shoulder 14 of Figs. 2 and 3. The parts above the base 27 are exactly those illustrated in Figs. 2 and 3, and therefore do not require to be re-described or shown in detail. 90

In Fig. 8 I illustrate the check protector of Figs. 1 to 4 inclusive in side elevation and as applied to a tube 32, the clamping fingers 13 tightly engaging the inner walls of said tube and which tube serves as a handle by which the check protector may be conveniently operated, said tube taking the place of the fountain pen cap. The device shown in Fig. 8 may be conveniently carried in one's pocket and made use of whenever desired. In Figs. 6 and 7 I illustrate a 100 modified construction of my check protector, and the same is shown as being adapted to be applied to a fountain pen or to the tube 32 shown in Fig. 8. In Fig. 6 33 denotes the base portion of the protector, and this portion is concaved on its lower side to fit upon a fountain pen and provided with clamping fingers 34 which correspond with the fingers 13 hereinbefore described and are used for the same purpose. The base 33 has an upwardly extending sleeve portion 35 which is annularly recessed, as at 36, to form an annular flange 37 which is internally threaded and also to form an annular shoulder 38 which affords a support 105 for the ends 39 of the axle or shaft for the roller ink-pad 40. Within the threaded flange 37 connected with the base 33 I apply a frame 41, shown in Fig. 7, carrying the toothed puncturing roller 42, which corresponds exactly with the roller 25 of Figs. 2 and 3. The frame 41 is formed with a lower annularly extending threaded band or ring 43 which is formed in its opposite sides with the downwardly opening recesses 44 to re-

95

ceive the ends of the axle or shaft 39 of the pad-roller 40. The ring or band 43 may be screwed downwardly into the recess 36 and engage the threads on the flange 37, and said 5 ring or band 43 has projected upwardly from opposite sides of the upper edge thereof of a pair of standards 45 containing vertically elongated openings 46 serving as bearings for the ends of the axle or shaft 47 of 10 the puncturing roller 42. The roller 42 is mounted between the standards 45 with the ends of its axle or shaft loosely held within the vertically elongated openings 46, which 15 openings 46 correspond exactly with the openings 23 in the standards 22 shown in Figs. 2 and 3.

In assembling the parts of the protector shown in Figs. 6 and 7, I find it convenient to turn the frame 41 carrying the roller 42 20 upside down and then drop the ends of the axle or shaft of the pad-roller 40 into the recesses 44 of the ring or band 43, whereupon I screw the base member 33 upon the said ring or band 43, after which the protector 25 may be turned to upright position, leaving the parts in the relation they occupy in Fig. 6. At this time the cap 48 corresponding with the cap 26 of Fig. 2, may be applied over the roller 42 and the protector 30 may be applied to the end of a fountain pen. The upper exterior edges of the sleeve portion 35 is recessed and threaded, as at 49, to receive the inner threaded lower end of the cap 48, as shown in Fig. 6.

In the several forms of my invention shown I provide a highly efficient and very compact check protector which may be conveniently carried on a pen or separately in one's pocket for use at any time a check 35 may be drawn. The ink pad-roller is a very desirable addition to the protector and increases its efficiency, but I do not wish to be limited in every instance to the use of the pad roller, since the puncturing roller 40 very efficiently acts as a check protector regardless of the presence of the ink roller.

I have shown and described the most efficient forms of my invention at present known to me but do not wish to be limited 50 to all of the details of form and construction described, since I am aware that these details may be modified without departure from my invention and within the scope of the appended claims.

What I claim as my invention and desire 55 to secure by Letters-Patent, is—

1. A check protector comprising a support having an annular vertical upwardly extending threaded flange portion, a removable frame threaded to engage said flange and having upwardly extending side standards, a puncturing roller having a series of

sharp-pointed teeth over its surface and journaled in said standards, and a removable cap adapted to conceal and protect said 65 roller and frame.

2. A check protector comprising a handle affording on one end a base member having an annular threaded sleeve extending above the same, a cylindrical frame having a 70 threaded lower portion engaging the thread on said sleeve and affording outwardly extending side standards, an ink pad roller positioned within the inner portion of said frame, a puncturing roller journaled in said standards over and in parallelism with said pad roller and adapted to engage the same and a removable cap fitting over said frame and rollers, said puncturing roller having 75 a series of rows of sharp pointed teeth over 80 its surface.

3. A check protector comprising a supporting base having an annular threaded sleeve extending above the same, a roller ink-pad whose shaft ends are supported on 85 said sleeve, a frame comprising a lower annular threaded portion engaging the thread on said sleeve and vertical standards extending above the same, a puncturing roller journaled in said standards over and in 90 parallelism with said pad and adapted to engage the same and having a series of rows of sharp-pointed teeth over its surface, a removable cap fitting over said rollers, and means associated with said base serving as 95 a handle for operating the puncturing roller against a check and the like.

4. A check protector comprising a supporting base having an externally threaded annular sleeve extending above the same, a 100 roller ink-pad whose shaft ends are supported on said sleeve, a frame comprising a lower internally and externally threaded annular member engaging the thread on said sleeve and vertical standards extending 10 above the same, a ring jamb nut on said sleeve adapted to engage said member for locking said frame in fixed position, a puncturing roller journaled in said standards over and in parallelism with said pad 11 and adapted to engage the same, and a removable cap fitting over said rollers and threaded to engage the external thread on said annular member.

5. A check protector as claimed in claim 1 2, in which said standards have vertically elongated openings for the ends of the shaft of said puncturing roller to permit a light engagement of the said roller with the ink-pad roller when the device is not in use.

Signed at New York city, in the county of New York and State of New York, this 6th day of September A. D. 1922.

MARCUS B. BEHRMAN.
